(57) **CLAIM**

The ornamental design for a display screen for digital camera with animated graphical user interface, as shown and described.

DESCRIPTION

FIG. 1 is a top, rear and left side perspective view of a display screen for digital camera with animated graphical user interface showing the first image of my new design; FIG. 2 is a rear elevational view thereof; FIG. 3 is a rear detail view of the display screen thereof; FIG. 4 is a rear detail view of the display screen thereof, showing the second image; FIG. 5 is a rear detail view of the display screen thereof, showing the third image; FIG. 6 is a rear detail view of the display screen thereof, showing the fourth image; FIG. 7 is a rear detail view of the display screen thereof, showing the fifth image; and, FIG. 8 is a rear detail view of the display screen thereof, showing the sixth image.
The broken line of showing of the digital camera forms no part of the claimed design.
The grayscale in the drawings indicates a contrast of appearance and forms part of the claimed design.

1 Claim, 8 Drawing Sheets
